SHUTTER MECHANISM FOR PHOTOGRAPHIC APPARATUS.

Application filed January 21, 1928, Serial No. 248,388, and in Switzerland January 29, 1927.

The present invention relates to a shutter mechanism for photographic apparatus in which the opening and closing of the shutter are automatically controlled from a spring barrel and in which a delay mechanism setting the beginning of the running down movement of the spring barrel is provided for. The improvement concerns the particular interconnection of the delay mechanism and the spring barrel, this interconnection being obtained by means of a locking lever arranged in such a manner that on resetting the delay mechanism it is brought into locking position with respect to the spring barrel and locked therein until on the running down movement of the delay mechanism the locking lever becomes unlocked and releases the spring barrel.

The accompanying drawing shows a constructional example of the improvements according to the invention.

Figure 1 shows the whole mechanism in normal condition with the shutter closed and with a shutter controlling device not under tension.

Figure 2 is a detail view.

The shutter mechanism illustrated comprises the usual shutter consisting of a plurality of movable blades 7, a driving spring barrel 5 with its usual winding up means for moving the blades to open or shut the shutter, a control mechanism A for regulating the timing of the running down of the spring barrel shown on the right in the drawing whose construction may be of any desired type and is therefore not shown in detail, and a delay mechanism B shown on the left in the drawing which is provided with a special spring barrel and according to its own adjustment times the beginning of the movement of the driving spring barrel 5. Control mechanism A and delay mechanism B are arranged in an annular casing C with the shutter centrally disposed within.

When the spring of the spring barrel 5 on whose periphery a control rib 5^a is formed is put under tension through its usual winding up or tensioning means, the spring barrel 5 is turned in a counterclockwise direction so far out of the position shown in Figure 1 that it is locked by a locking lever 4 which falls into engagement with the rib 5^a. This lever is pivoted on the pin 4^a and is influenced by a spring 4^b which acts on the pin 4^c of the lever 4 and tends to move the lever into the locking

position. At its upper end the locking lever 4 is controlled by the release mechanism.

This release mechanism comprises a knob 1 (Figure 1), adapted to be operated by the finger or otherwise, which when moved pushes forward a part 2 and thus turns the member 3 about 3^a against the action of the spring 3^b. Towards the end of this movement the part 3^c of the member 3 abuts against the backwardly projecting pin 4^d of the lever 4, 65 and on further movement turns this lever about its pivot 4^a until its shorter end disengages from the rib 5^a of the spring barrel 5, releasing the latter for the opening stroke of the shutter blades and the running down 70 movement of the shutter control mechanism A.

The opening and shutting of the blades 7 of the shutter, each of which is pivoted on a pin 7^a of the base plate, is effected by the 75 spring barrel 5 turning a ring 6 broken away on the drawing, to which the blades are linked at 7^b. (The details of the mounting and connection of the blades 7 are represented only for one of same.) The ring 6 is controlled by 80 a hook 6^a which is linked at 5^b to the spring barrel 5 and co-operates with a pin 6^c of the ring 6 when the spring barrel 5 turns about its axis in a clockwise direction. During the 85 rotary motion of the spring barrel, which extends over an angle of about 180°, the hook 6^a has a reciprocatory movement like a crank connecting rod thus causing the movement of the ring 6. In its forward movement the hook 6^a abuts with its tooth 6^d against the pin 6^c, 90 as soon as it is allowed to do so by the guide pin 6^e against which it slides under the influence of the spring 6^f, whilst the return movement of the ring 6 is effected by the hook piece 6^g of the hook 6^a as soon as the 95 spring barrel 5 pulls the hook in the return direction. When the spring barrel 5 is being wound up or put under tension, the hook 6^a slides against the pin 6^e, and until the tension is complete it does no more engage with 100 the pin 6^c, which is held by the spring 6^b against undesired movements from shock and the like. As can be seen, owing to its crank like drive, the hook 6^a in the middle part of its stroke has hardly any longitudinal movement.

The spring barrel 5 is further under the control of the above mentioned delay mechanism B. This comprises, as above mentioned, a special spring barrel 10 with the 110

usual winding up or tensioning means against whose periphery lies a spring pressed pawl 9 pivoted at 9^a, and which has a notch 10^a on its periphery. The pawl 9 supports a locking lever 8, which is also pivoted on the pin 4^a and serves as a further locking means for the spring barrel 5 when the delay mechanism B is under tension or wound up.

If after the spring barrel 5 is put under tension the delay mechanism has also been put under tension, on pressure of the knob 1 the lever 4 disengages from the spring barrel 5, but this latter is still retained by the locking lever 8 held in the locking position by the pawl 9, after it has turned so far that on releasing the pressure on the knob 1 the lever 4 can no longer engage the rib 5^a, but rests on its periphery in the manner shown in Figure 2. The locking end of the lever 8 has an oblique end surface on which the edge of the rib 5^a of the spring barrel 5 exerts a pressure on the lever 8 in the direction of the arrow in Figure 2, which forces this to release the spring barrel 5 as soon as it is released by the pawl 9. This occurs as soon as the tensioned delay mechanism has run down and the notch 10^a of the spring barrel 10 lies opposite the hook shaped end of the pawl 9. At this instant the locking lever 8 loses its support on the pawl 9, it yields to the spring pressure and the spring barrel 5 can proceed with its rotary movement to perform its further functions. The notch 10^a has an oblique edge at one end so that when the delay mechanism is tensioned the pawl 9 can be easily raised out of the notch.

The tensioning of the delay mechanism B is effected by turning the spring barrel 10 whose movement is limited by an abutment 46 on the underside of the base plate (not visible in the drawing) so that its greatest movement is limited to about 300°. After the delay mechanism has been put under tension therefore the pawl 9 cannot fall into the notch 10^a (Figure 2) even if the delay mechanism is not completely tensioned to obtain a shorter delay.

The locking lever 4 has a projection 4^b which, in the tensioned condition of the spring barrel 5 and so long as the knob 1 is not depressed, holds the escapement pawl 29 of the delay mechanism B out of engagement with the escapement wheel 29^a, so that the delay mechanism can be tensioned, it being effected by pressing back the arm 30 which is pivoted at 30^a and carries the escapement pawl 29, against the action of the spring 30^b. If the lever 4 is released, its projection 4^b releases the arm 30 and this swings the escapement pawl 29 inwards so that the part 30 abuts against the abutment 30^a.

Beneath the lever 4 there is a locking pawl 11, which when the spring barrel 5 is tensioned and the lever 4 has engaged with the rib 5^a of the spring barrel 5, prevents the tensioned spring barrel 10 of the delay mech-

anism from running down before the release by engaging the teeth on the same. On depression of the knob 1, the movement of the lever 4 produced thereby causes the pin 4^c of the same to lift the locking pawl 11 out of engagement with the teeth of the spring barrel, and the delay mechanism begins to run down.

The shutter mechanism can work with or without the delay mechanism.

(1). *Without delay mechanism.*—The spring barrel 5 is tensioned so that it is locked by the levers 4 and 8. On depressing the knob 1, the lever 4 is caused to disengage with the rib 5^a of the spring barrel 5, and the lever 8, which has no further locking support on the pawl 9, is swung out by the pressure of the spring barrel 5 on its oblique end surface, thus releasing the spring barrel 5 so that the shutter can be freely operated according to the ratio of transmission of the shutter control mechanism A.

(2). *With delay mechanism.*—The spring barrel 5 is tensioned so that it is locked by the levers 4 and 8. By the movement of the lever 4 the escapement pawl 29 of the delay mechanism B is lifted out of operative engagement and the delay mechanism can therefore be put under tension. The locking pawl 11 prevents the same running down at once. The pawl 9 rests with its free end on the smooth upper surface of the spring barrel 10. On depressing the knob 1, the lever 4 is moved and thus releases the spring barrel 5, whose rib 5^a at once abuts against the lever 8. The latter, however, cannot yield for it is locked on the pawl 9. At the same time the movement of the lever 4 releases the escapement pawl 29 of the delay mechanism and lifts the pawl 11 out of the teeth of the spring barrel 10 so that the delay mechanism can begin its movement. The spring barrel 10 turns about an angle of approximately 300°, or an angle corresponding to the degree of its tensioning until the pawl 9 falls into the notch 10^a. Thus the support is removed from the lever 8 and the same yields to the pressure of the spring barrel 5 so that the latter can turn and the blades 7 are operated.

If the shutter mechanism is used in the way above described its working speed, that is the length of time between opening and shutting is only dependent on the strength of the spring of the spring barrel 5 as driving element and the operation of the control mechanism A, which as above mentioned can be of any desired construction and has only to brake or regulate the running of the spring of the spring barrel 5. The latter makes about a half revolution which is quite enough to oscillate the ring 6 for opening or shutting the shutter by means of operating the hook 6^a like a reciprocating connecting rod.

What I claim is:

1. In a shutter mechanism for photo-

- graphic apparatus, a movable shutter, a driving spring barrel, connecting means between the driving spring barrel and the shutter, an automatically controlled locking lever for said driving spring barrel, a spring barrel delay mechanism arranged to bring said automatically controlled locking lever into locking position when being put under tension and to hold same therein, and means, controlled by said delay mechanism, for allowing said automatically controlled locking lever to release the driving spring barrel on running down of the delay mechanism.
2. In a shutter mechanism for photographic apparatus, a movable shutter, a driving spring barrel, a hand operatable locking lever therefor, connecting means between the driving spring barrel and the shutter, an automatically controlled locking lever for said driving spring barrel, a spring barrel delay mechanism arranged to bring said automatically controlled locking lever into locking position when being put under tension and to hold same therein and means, controlled by said delay mechanism, for allowing said automatically controlled locking lever to release the driving spring barrel on running down of the delay mechanism.
3. In a shutter mechanism for photographic apparatus, a movable shutter, a driving spring barrel, connecting means between said driving spring barrel and the shutter, an automatically controlled locking lever for said driving spring barrel, a spring barrel delay mechanism, a movable support piece controlled thereby for supporting the said automatically controlled locking lever in locking position with respect to the driving spring barrel, and means to allow yielding of said support piece on running down of the delay mechanism and to thus allow the automatically controlled locking lever to release the driving spring barrel.
4. In a shutter mechanism for photographic apparatus, a movable shutter, a driving spring barrel, connecting means between said driving spring barrel, an abutting part on the latter, an automatically controlled locking lever for said driving spring barrel having an oblique abutting surface at its end cooperating with the abutting part of said driving spring barrel, a spring barrel delay mechanism, a movable support pawl arranged to cooperate with a movable member thereof, said pawl being provided with means to support the said automatically controlled locking lever in locking position with respect to the driving spring barrel, and means to allow yielding of said support pawl on running down of the delay mechanism for the purpose of allowing the automatically controlled locking lever to release the driving spring barrel owing to the pressure of the abutting part thereof upon the oblique end surface of said lever.
5. In a shutter mechanism for photographic apparatus, a movable shutter, a driving spring barrel, a hand operatable locking lever therefor, connecting means between said driving spring barrel and the shutter, an automatically controlled locking lever for said driving spring barrel, a spring barrel delay mechanism arranged to bring said automatically controlled locking lever into locking position when being put under tension and to hold same therein, means dependent on said hand operatable locking lever to lock said delay mechanism and means controlled by said delay mechanism for causing the automatically controlled locking lever to release the driving spring barrel on running down of the unlocked delay mechanism.
6. In a shutter mechanism for photographic apparatus, a movable shutter, a driving spring barrel, a hand operatable locking lever therefor, connecting means between said driving spring barrel and the shutter, an automatically controlled locking lever for said driving spring barrel, a spring barrel delay mechanism arranged to bring said automatically controlled locking lever into locking position when being put under tension and to hold same therein, said delay mechanism comprising an escapement wheel and a pawl device for regulating purposes, means dependent on said hand operatable locking lever to engage or disengage said escapement device of the delay mechanism, and means controlled by said delay mechanism for causing the automatically controlled locking lever to release the driving spring barrel on running down of the unlocked delay mechanism.
7. In a shutter mechanism for photographic purposes, a movable shutter, a driving spring barrel, connecting means between said driving spring barrel and the shutter, an automatically controlled locking lever for said driving spring barrel, a spring barrel delay mechanism having a notched rotary element, a spring urged pawl engaging said notched rotary element, and means on said pawl to support and hold said automatically controlled locking lever in locking position with respect to the driving spring barrel when being put under tension, substantially as and for the purpose described.

In witness whereof I have hereunto signed my name this 7th day of January, 1928.

JACQUES WOLF.
